Whole No. 1403.

J. B. Sargent, of New Britain, Conn.
Letters Patent No. 38, dated April 30, 1861.

The schedule referred to in these Letters Patent and making part of the same.

To all whom it may concern:

Be it known that I, J. B. Sargent, of New Britain, in the County of Hartford, and State of Connecticut, have invented, or produced a new and original Design for a Hive Box, and I do hereby declare that the following is a full, clear, and exact description thereof, reference being had to the accompanying drawings, making a part of this specification, in which-

Similar letters of reference indicate corresponding parts in both Figures.

This invention consists in a hive box shaped like a bee hive and having a suitable border surrounding its base, which gives a neat & pretty finish to the hive box: and the whole taken together forms an useful and ap-appropriate ornament for the counter of a store, as will be seen from the following description and a reference to the accompanying drawings.

A. is a hollow box, the exterior configuration of which is that of a bee hive, having flutings a, a, a, a, which surround the box as shown in the drawings; and a horizontal section through the box A, shows it to be of a circular shape, from its base to its apex or crown. The annular horizontal ribs or flutings a, a, a, a, are what give to the box A, the appearance of an old fashioned bee hive.

Surrounding the bottom edge of the hive box A, and projecting out therefrom so as to give a wide base to the box A, is a border B, the exterior surface of which should be ornamented with imitations of leaves or with any other neat and handsome design.

What I claim as new and desire to secure by Letters Patent is
The design of the bee hive twin box A, with its border B, as shown and described.
